SAFETY MATCH BOOK

Otto V. Johnson, Minneapolis, Minn.

Application August 9, 1937, Serial No. 158,180

3 Claims. (Cl. 206—29)

My invention relates to improvements in match book structures adapted for use in connection with match cards or the like.

One of the principal objects of my invention is to provide a match book structure equipped with means whereby matches carried within the structure are protected from accidental igniting from a match ignited on the igniting medium carried by the book.

10 Another object of my invention is to provide a structure of the above described character fashioned with means for supporting the book in an upright position which may be readily detached therefrom when desired.

15 Other objects and advantages will be apparent from the following description, appended claims and annexed drawing.

Referring to the drawing wherein like reference characters designate like parts throughout 20 the several views:

Fig. 1 is a perspective view of my invention.

Fig. 2 is a side elevation thereof, partly in section, illustrating the match cards positioned therein.

25 Fig. 3 is an end elevation thereof.

Fig. 4 is an end elevation of the blank from which the body is formed, the same being illustrated in an extended position.

Fig. 5 is a perspective view of a modified form.

30 Fig. 6 is a perspective view of another modification.

In teaching my invention, in the preferred form illustrated in Figures 1 to 4 inclusive of the drawing, I provide a one-piece elongated pliable body 7, preferably constructed of cardboard, folded in a manner to form a fold section 8 on one end thereof and free ends 9 on the opposite end thereof. The fold section comprises downwardly and outwardly inclined folded support members 10 having a centrally disposed jointure 11 and terminating in spaced sides 12. The sides, adjacent the free ends 9, are formed with upwardly and inwardly inclined sections 13 having abutting faces 14. Each of the sides has arranged thereon adjacent the support members 10 a match igniting medium 15 formed with a suitable substance for igniting matches engaged therewith. Interposed between the sides 12 and above the jointure 11 are a pair of match cards 16 having slit sections forming match bodies 17 equipped with ignitable match heads 18. The match cards are secured to and between the sides 12 by means of suitable staples 19 or the like. Each of the outer walls of the support members 10 at the upper ends thereof is formed with perforations 20

whereby said support members may be readily detached from the sides 12 by a manual tearing or severing operation.

The support members 10 provide a suitable support for the body which is adapted to be maintained in a substantial vertical position on any suitable support for household use or the like. 5

When it is desired to extract a match from one of the match cards, the free ends are moved from engagement with each other a sufficient distance 10 to permit the removal of a match and after said removal, due to the resiliency of the sides, move together to effect abutting engagement of the faces 14. Each of the sides 12 is formed, intermediate of the respective upper and lower ends, 15 with a fold section 12a to provide inwardly and upwardly inclined portions 12b, said portions functioning to urge the faces 14 into engagement with each other and thereby maintain the ends in closed position. 20

The spaced relation of the sides 12 together with the closed top formed by the free ends abutting each other provide a protective pocket or chamber for the unignited matches therein and prevent the same from becoming accidentally ignited from a match ignited by the medium 15. 25

In instances where it is desired to use the match book for pocket use, the support members may be detached from the sides at the perforations 20.

30 In the modification illustrated in Fig. 5, the sides 25 are connected together by a single fold 26 and the support members 27 are provided with free ends 28 embracing the fold and secured to the body by means of staples 29. The match igniting medium 30 is arranged on the outer faces of the free ends 28 of the members 10.

In instances where it is desired to have a match book for pocket use only, the sides 35 are formed with a single lower fold 36 on which is 40 arranged the match igniting medium 37. A suitable staple 38 secures the match cards within the fold and to the sides 35.

45 It is to be distinctly understood that various changes and modifications in construction and arrangement of parts may be resorted to without departing from the spirit of the invention or scope of the appended claims.

Having described my invention, what I claim is:

50 1. In a match book structure, an elongated pliable body fashioned with a folded section between the ends thereof and provided with spaced sides having inner opposed faces, the ends of said body having inwardly and upwardly extending offset 55

- portions, and a match card formed with matches and secured between said sides and coacting therewith to maintain said sides in spaced relation adjacent said offset portions, said sides bent 5 between said ends and folded section for urging said offset portions together whereby said inner faces of said sides abut each other above the heads of said matches to enclose and protect the latter from accidental ignition.
- 10 2. In a match book structure, an elongated pliable body fashioned with a folded section between the ends thereof and provided with spaced sides having inner opposed faces, the ends of said body having inwardly and upwardly extending 15 offset portions, and a match card formed with matches and secured between said sides and coacting therewith to maintain said sides in spaced relation adjacent said offset portions, said folded section fashioned with a pair of folded members for supporting said structure including said 20 card in upright position, said sides bent between said ends and folded section for urging said offset portions together whereby said inner faces of said sides abut each other above the heads of said matches to enclose and protect the latter 25 from accidental ignition.

3. In a match book structure, an elongated pliable body fashioned with an intermediate folded section forming spaced sides having inner opposed faces and terminating in free ends provided with offset portions, a match card formed 5 with matches and secured between said sides and coacting therewith to maintain said sides in spaced relation adjacent said offset portions, said folded section fashioned with a pair of folded members for supporting said structure including 10 said card in upright position, said sides bent between said ends and folded section for urging said offset portions together whereby said inner faces of said sides abut each other above the heads of said matches to enclose and protect the latter 15 from accidental ignition, and a match igniting medium arranged on one of said sides on the outer face thereof adjacent said folded section whereby said last mentioned side and offset portions isolate said medium from said match card 20 to prevent accidental igniting of matches on said card by the igniting of a match on said medium when said inner faces are in abutting engagement.

OTTO V. JOHNSON. 25
